CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a display screen or portion thereof with graphical user interface showing our new design.

The peripheral dashed broken lines illustrate a display screen or portion thereof, and form no part of the claimed design.

The shapes defined by black solid lines form part of the claimed design; the faded portions within and outside the black solid lines form no part of the claimed design.

The dotted broken lines illustrate a boundary which forms no part of the claimed design. The masked portion within the dotted broken lines forms no part of the claimed design.
